CLAIM

The ornamental design for a street light, as shown and described.

DESCRIPTION

FIG. 1 is a perspective view of the new design for a street light having round-shaped cooling fins for solid state lighting;

FIG. 2 is a right side view thereof, the left side view being a mirror image of the right side view shown;

FIG. 3 is a front view thereof, the rear view being a mirror image of the front view shown;

FIG. 4 is a top view thereof; and,

FIG. 5 is a bottom view thereof.

Broken lines are used to show a mounting structure, such as a pole, that forms no part of the claimed design.
